UNITED STATES PATENT OFFICE.

JOHN GEORGE TUFFORD, OF ELYRIA, OHIO.

RUBBER HEEL.

Application filed December 23, 1921. Serial No. 524,516.

To all whom it may concern:

Be it known that I, JOHN GEORGE TUFFORD, a citizen of the United States, residing at Elyria, in the county of Lorain and State of Ohio, have invented certain new and useful Improvements in Rubber Heels, of which the following is a full, clear, concise, and exact description, such as will enable those skilled in the art to which my invention appertains to make and use the same.

My invention relates to rubber heels, and more particularly to what are known in the art as rubber whole heels, said heels being adapted to be directly attached to the curved heel or rear part of the sole of a shoe.

It is an object of my present invention to provide such a rubber whole heel, which may be directly attached to the curved heel of a short sole by nails or other attaching means, said nails being driven through openings in the rubber heel into the said sole, and which when so secured will make a tight fit at the edges of the heel with those portions 25 of the shoe heel with which they come in contact.

It is furthermore an object of my invention to enable heels of this nature to maintain, without the use of cement, tight edges continuously while in use, said tight edges being alone secured through the inherent resiliency of the rubber material of which the heel is made.

Another object of my invention is to construct such a heel, as aforesaid, having normally an attaching face with a deeper concavity than is required to fit the convexly arched surface of the shoe heel so that when the rubber heel is secured to the said convexly arched heel portion of the sole, a partial flattening of the said rubber heel concavity will be required, in order to bring the concave attaching face of the heel into contact with the said convexly arched opposing faces of the shoe heel. I then position the nails or other attaching means, so that the concave face will be maintained partially flattened, and so that the effort of the heel to resume its normal unstressed condition will maintain the tightness of the seam be-

tween the heel and the bottom of the shoe.

The curvature of the attaching face is of such degree and kind that the attempt to press it closely against the commercial shoe heels or rear sole ends, will result in such flattening of the attaching face of the rubber heel that the seam will be sealed by the retractive effort of the rubber in the heel.

In the embodiment shown, that part of the attaching face towards the outside edge outside the line of nail holes is curved very sharply thus insuring a tight clinging action by the edge of the rubber heel to the leather heel all during the use thereof even though the curvature of the shoe heel or rear end of the sole may vary within certain limits which I find in practice to be the practical limits of commercial heels. By increasing the curvature, that is, by reducing the radius of curvature as the edge is approached, the sealing effect at the edge is intensified.

Other objects of my invention and the invention itself will be more apparent by reference to the specification and drawings, which are a part of this specification, and which illustrate an embodiment of my invention. In these drawings.—

Fig. 1 shows a bottom plan view of a rubber shoe heel embodying my invention.

Fig. 2 shows a top plan view of the heel.

Fig. 3 shows a front elevation of the heel, the heel being shown as inverted, or, rather as in the position taken when the heel is to be attached to the bottom of an inverted shoe.

Fig. 4 shows a rear elevation of the heel.

Fig. 5 shows a side elevation of the heel.

Fig. 6 shows a transverse section of the rubber shoe heel taken on the line 6—6 of Fig. 1.

Fig. 7 shows a longitudinal, medial section of the heel taken on the line 7—7 of Fig. 1.

Fig. 8 shows a side elevational view of the rubber shoe heel placed upright, and a portion of the rear of a shoe placed over the shoe heel, the view being taken before the heel is attached to the bottom of the shoe

by the securing nails, the heel being in its undistorted, normal shape.

Fig. 9 shows a transverse section on the line 9—9 of Fig. 8.

5 Fig. 10 shows a longitudinal, medial section of the shoe heel and shoe rear portion, illustrated in Fig. 8.

10 Fig. 11 is a side elevational view of the rear part of a shoe, with the shoe heel attached as by nails to the shoe openings provided in the heel.

Fig. 12 is a section on the line 12—12 of Fig. 2.

15 Referirng now to the drawings, in the various figures of which like parts are designated by like reference characters, at 2 is shown a rubber heel adapted to be secured to the convexly arched bottom 3 of the shoe, said heel having sides 4 and 5, a breast 6, 20 a rear side 7, a tread face 20, and an attaching face 8, and which attaching face contains a centrally disposed recess, 9.

25 The recess 9 is preferably, substantially annular in shape, the sides being irregular shaped, there being abutments at 30 and 31 at the sides, 32 and 33 at the rear corners, and 34 and 35 at the forward corners of the recess; these abutments being provided in order that the nails may be driven there- 30 through, the material of the abutments having nail head supporting washers embedded therein. Thus the nails may be removed further from the side edges of the heel. This gives the heel greater life and trim- 35 ming area, since most of the wear is at the edges and generally at the rear edges of the heel; also the cobbler can keep fewer sizes of heels in stock, since, on account of the greater trimming area, a larger heel can be 40 trimmed to fit a smaller shoe, than is commonly the case. In the center of the so-called annular recess 9, there is provided a raised, substantially circular portion of rubber in the recess, the top of which is substantially as high, relative to the bottom of the recess, as the top sides of the recess walls; shown at 36.

45 That portion of the attaching face which is adapted to come into contact with the convexly arched shoe heel 3 when the rubber heel 2 is flattened against the said heel, comprises that portion 10 of the face between the said recess and the outer edges. The portion 10 of the attaching face ex- 50 tends all around the outside of the recess and is a relatively narrow portion, trans- versely curved, the curvature being relatively sharp compared with the curvature of the shoe heel, and with which it is adapt- 55 ed to contact. When the rubber heel is, therefore, attached to the bottom of a shoe, as illustrated in Figs. 7 to 11 inclusive, the nails will be driven through the rubber heel from the tread face side, said nails penetrat- 60 ing the attaching face portion, 10, inter-

mediate the attaching face outer edges and the recess 9, so that the transverse arches will be caused to be held down at intermediate portions, causing a partial flattening of the said arches, and power will be trans- 70 mitted to the outer edges of the rubber heel, to seal the seam at these edges, said seam being continuously sealed by the retractive effort of the rubber in the heel. The portion 10 of the attaching face about the central 75 portion of the attaching face is, in the em- bodiment illustrated, somewhat of the na- ture of a groove, the outer edges 21 being 80 relatively elevated to the inner edges 22, the groove containing an intermediate por- tion between the edges 21 and 22 which is depressed with respect to a line joining these two edges and at right angles to the longitudinal direction of the groove. The center nail may be omitted when desired, 85 having little or no part in securing the tight edge function.

89 While the particular shape of the groove may vary somewhat, I prefer to make this groove of that shape which is illustrated in 90 the drawings, wherein that portion of its face 10, which is nearest the recess 9, is curved on a longer radius than more distant portions nearer the outer edge of the heel, certain advantages being gained by 95 such construction, although my invention in its broader phases will be had in a construc- 100 tion wherein the degree of curvature of the so-called groove constituting the portion 10 of the attaching face of the heel is the same near the recess as nearer the outer edge.

105 The tread face of the heel is preferably curved both transversely and longitudinally, my invention broadly considered, being cap- 110 pable of embodiment, however, in heels whose tread face is only curved longitudinally and not in a direction at right angles thereto, or in heels whose tread face has transverse curvature only, but not in a long- 115 itudinal direction at right angles thereto.

120 However, my preferred embodiment has a tread face as illustrated curved in all di- 125 rections, and I prefer also, as illustrated, to make the heel with a tread face having the same radius of curvature in every di- 130 rection, as I find that such a heel with an attaching face as illustrated and described herein accomplishes the most efficient result when secured to the bottom of a shoe heel, not only in the tightness with which the 135 seam is sealed at its edges, but in securing a tight seam with the minimum of necessary trimming, and at the same time producing a heel, which, when secured by nails positioned as illustrated, will have the least 140 tendency toward removing the said nails since the stresses which otherwise might be effective to remove the nails in other constructions, are herein more nearly balanced.

145 Also, I find that with the attaching face

substantially as illustrated and with a tread face which is substantially, as above described, a true portion of a sphere, that where such a heel is attached to the bottom 5 of a shoe heel as ordinarily shaped and as such shoe heel shapes may vary in practice, accomplishes the additional result of securing a substantially flat tread face when the heel is put into use.

10 Nail receiving openings are exposed on the tread face, being arranged so that nails driven therethrough will pierce the arched portion 10 of the attaching face, to partially flatten the same, to bring its walls into intimate contact with the contacting faces of the heel of the shoe. When so secured in place, the heel by its inherent resiliency, in its efforts to regain its normal shape, will compress the portions of the attaching face 15 of the heel against the shoe heel, to seal the seam all around the heel, so as to prevent the ingress of dirt and moisture to the interior spaces between the sole and the rubber heel, such, in the embodiment illus- 20 trated, comprising the recess, 9. Also, when the nails are in place, the arched tread face will be caused to be substantially flat, being so held against the retractive force of the rubber in the heel by the nails 25 driven through the rubber heel into the bottom of the shoe.

30 By my improved construction, the effort of the nails is transmitted through the resilient rubber of the body of the heel to the seams at the breast and rear edge portions of the heel to keep them tight; even though no nails are used at the front and rear longitudinal medial portions. The omission of the rearmost nail, as illustrated 35 in this embodiment, provides more space on this portion of the rubber heel, which is most subject to wear, to wear away, without causing securing nails to be exposed, and which difficulty is experienced with other 40 constructions, but which difficulty would be entirely absent in the construction of the embodiment herein illustrated.

45 The heel may be trimmed to fit the shoe sole perfectly, either before, or preferably 50 after, attachment, the edge sealing function being operative to seal the same after trimming, as before, and the nails being relatively remote from the edges permit considerable trimming of the edges to be ac- 55 complished, without exposing the said nails at the edges.

60 The heel illustrated and described herein is constructed substantially entirely of rubber or like material and does not require a reinforcing metal plate or like reinforcement to secure the seam sealing effect; such reinforcements are a source of trouble in a number of ways among which they do not maintain the seams tightly sealed, they

65 prevent the resilient rubber material when bent to regain its normal edged seam sealing position, they make the heel less resiliency, that is, harder to walk upon, and they limit the trimming area as well as to make the heel heavier. 70

75 While the heel of my invention may be trimmed to a maximum degree, the heel will find a very advantageous use where sufficient sizes are kept in stock so that little or no trimming will be required in many cases. In most heels, the heels after being secured in place on the bottom of the shoe heel, the side edges are not straight as are the side and rear faces of the heel of my invention which after attachment are vertical, and this construction limits the amount of trimming required. 80

85 Also, the shape of the heel as illustrated insures that the bottom or tread face is substantially level after the heel is secured to the bottom of a shoe; this contributes to ease in walking on the heel and makes a more comfortable heel to walk upon. 85

90 Having thus described my invention, I am aware that numerous departures may be made from the specific embodiment there- 95 of, herein illustrated and described, for the purpose of illustrating and explaining my invention, but which departures would be within the spirit of my invention. 95

I claim:

A "whole" type rubber heel adapted for attachment to the convexly rounded bottom of a shoe sole, having a lower convex tread face, and an upper concave attaching face, said attaching face comprising an approximately U-shaped grooved border portion extending parallel with and directly adjacent the sides and rear of the heel, the groove 100 thereof being arched transversely of its length, the arching thereof being sharper than the arching of the convexly rounded shoe sole bottom portion with which it is adapted to contact, and the groove being transversely inclined from the side and rear 105 top edges of the heel downwardly and inwardly towards the central portion of the attaching face thereof, the central portion of the concave attaching face within the grooved border portion being substantially nonre-entrant above the plane of the lower- 110 most edge of the grooved portion, a plurality of nail receiving openings through the tread face adapted to direct heel securing nails through the said grooved portion of the attaching face, with the nail heads held in the body of the heel, the con- 115 formation of the said tread and attaching faces and the placing of the nail directing openings being such that nails passed through such openings and into the convexly rounded bottom of a shoe sole will 120 so distort the heel from its normal form 125

as to bring the surfaces of the heel groove portion and of the opposed shoe sole bottom into intimate contact, the tread face being thereby made approximately flat, and
5 the re-action of the distorted resilient rubber heel portions against the distorting power of the nails causing a tight sealing of

the seam between the contacting rubber heel side and rear edges and the shoe sole bottom.

10

In witness whereof, I have hereunto signed my name this 17th day of December, 1921.

JOHN GEORGE TUFFORD.
